UNITED STATES PATENT OFFICE.

WILLIAM ERICK BIHL, OF CHICAGO, ILLINOIS, ASSIGNOR TO IRON MOUNTAIN COMPANY, A CORPORATION OF ILLINOIS.

REFRIGERATOR CONTROL MECHANISM.

Application filed June 8, 1923. Serial No. 644,129.

The present invention relates to refrigerator control mechanism.

In domestic, portable and other types of refrigerators employing an electric motor for driving the refrigerator compressor, considerable difficulty has been encountered in providing a switch operating element which will be sufficiently accurate and sensitive in its operation, under the very slight changes of pressure incident in the heating and cooling of the refrigerator; and which will give sufficient amplitude of movement for actuating the circuit controlling member under the very slight change of pressure available for its operation.

Considerable difficulty has also been encountered in providing a circuit interrupter which will operate successfully on the very small actuating movement available from the switch operating element without injurious arcing and binding of the switch contacts. Reliability and positiveness of operation, and the ability to give continued service without repair are practically essential to the commercial success of these domestic and portable refrigerators, because of the continuous duty of the refrigerator and the expense of rendering service to refrigerators scattered over a large area of the country.

It is the fundamental object of the present invention to provide improved temperature responsive switch operating means which will be positive and reliable in operation, and which will give the maximum range of switch operating movement for a given pressure variation; also to provide in co-operation therewith an improved circuit interrupting member which will require only a very small amount of actuating movement to insure a positive, clean make or break of the motor circuit without the possibility of arcing or binding of the contacts.

Other objects will be apparent from the following description taken in connection with the accompanying drawings, in which I have illustrated a preferred embodiment of my invention.

In the drawings:

Fig. 1 is an assembly view of the compressor unit and the brine tank isolated from the remainder of the refrigerator structure.

Fig. 2 is a fragmentary side elevational

view of the control switch, with the cover plate of the switch housing removed, and

Fig. 3 is a horizontal sectional view through the switch housing.

Referring to Fig. 1, the compressor unit 60 5 comprises an electric motor 6 and a compressor 7 mounted upon a common base plate. A belt drive 9 connects the motor 6 with a driving wheel 11 on the compressor. A crank 12 is driven from the drive wheel 65 11 and reciprocates a piston or diaphragm in the compressor cylinder. This compressor cylinder is not shown, being disposed substantially centrally in a condensing or cooling chamber 13. The compressor cylinder 70 discharges into this chamber 13, and after being condensed or cooled therein the refrigerant is discharged through pipe 14 into the cylindrical receiver 15 which is mounted on the base plate 8 between the 75 motor and compressor. The refrigerant is cooled or condensed in the chamber 13 by coming into contact with a cold water cooling coil in the chamber. The cold water inlet is through a pipe 18 which opens into 80 a valve 19, and from this valve the cold water is conducted through pipe 20 to the inlet end of the cooling coil. The outlet from the coil is indicated at 21. The cold water controlling valve 19 is subject to automatic control, as I shall presently describe.

From the receiver 15 the refrigerant is conducted through a valve fitting 16 and through a pipe 17 to an expansion valve 30. This expansion valve discharges into a cooling chamber 22; in the indirect expansion installation shown, this expansion occurring into a series of coils contained in the chamber or tank 22. These cooling coils consist of a multiplicity of sinuated coils 23 extending between headers 24 and 25 in the top and bottom of the brine tank. These several coils 23 are submerged in a body of brine which substantially fills the tank 22 and which surrounds cooling chambers 26 95 extending transversely through the tank 22. The refrigerating fluid is withdrawn from the lower header 25 through a pipe 27 which extends down to the compressor unit and has connection with the compressor cylinder 100 through the intake connection 28.

The circuit controlling mechanism for the electric motor 6 is assembled in unit form upon a mounting plate or bracket 31 of angular form, this plate or bracket being se- 105

cured by bolts 32 to standards or uprights 33 on the main mounting base 8. Mounted on this bracket 31 is a central standard 34 which carries a pivot pin or shaft 35 for 5 pivotally supporting oppositely extending levers 36 and 37. Both levers have individual metallic bellows for imparting a tilting movement to them, said tilting movement being operative to make or break the motor 10 circuit through an actuating rod 41 pivotally connected to the end of the lever 37 and extending down into the switch housing 42. The bellows 38 bears at its upper end against the under side of the corresponding 15 lever 36, and has connection through its lower standard portion with a pipe 43 which connects with the condensing chamber 13. The expansion of the bellows 38 is opposed by a tension spring 44 which has connection 20 at one end around a pin 45 secured to the lower part of the mounting bracket 31, and at its upper end is connected with a screw eye 46 having adjustable attachment to the lever 36, whereby the tension of the spring 25 44 can be readily adjusted. When an excessive pressure is generated in the condensing chamber 13, this pressure is effective through the bellows 38 to rock the lever 36 upwardly. This lever has an extending end carrying 30 an adjusting screw 47 which is adapted to strike in the bottom of the channel-shaped lever 37 after the lever 36 has moved a predetermined amount. The extent of movement of the lever 36 before actuation of the 35 lever 37 can be varied by adjusting the screw 47. The initial part of the upward movement of the lever 36, upon an undesirable increase in pressure in the condensing chamber 13, operates through the adjustable rod 40 40 to open the cold water valve 19 to a greater extent. If the increased condensation resulting from the greater flow of cold water through the cooling coil does not result in stopping the undesirable increase in pressure, the continued expansion of the bellows 45 38 will rock the screw 47 down against the lever 37 and open the motor circuit by depressing the rod 41.

The bellows 39 has engagement with its lever 37, similarly to the engagement between the bellows 38 and lever 36, such as by a pin or stud 48 engaging in an opening in the bottom of the lever. A tension spring 49 is secured to a transverse pin 51 carried 50 in the mounting bracket 31, and at its upper end this spring has connection with an eye bolt 52 passing up through the bottom of the channel-shaped lever 37. An adjusting screw or nut 53 threads down over the bolt 52 and provides an adjustment for increasing or decreasing the tension of the spring 49. The tension spring 44 for the other bellows may have an adjustment similar to the 60 adjustment 52-53.

The bellows 39 is intended to be responsive

to the rise and fall of temperature in the brine tank 22, and to this end is connected to a closed end tube or chamber containing a fluid subjected to the temperature of the brine tank 22. This closed end tube or 70 chamber is formed in part by a pipe 54 which extends from the bellows 39 to a T connection 55 at the upper part of the brine tank. Extending downwardly from this T connection is a tube 56, the lower end of 75 which is hermetically sealed, and which is submerged in the body of brine permeating between the tubes 23. The temperature responsive fluid, which is a refrigerating liquid, is contained in this submerged tube 80 56. In the assembly of this control mechanism, a preferred practice is to pump a vacuum of as high as 30 inches on the line 56, 55 and 54 and the bellows 39, and then seal this line or chamber. The line or chamber is then charged with a predetermined amount of refrigerating liquid to a pressure of approximately 10 pounds. The bulk of this liquid will condense in the coldest portion of the system, i. e., in the submerged 85 tube 56 in the brine tank.

It will be apparent that as the brine rises in temperature, the pressure in the submerged tube and in the line 55-54 will rise. This increase in pressure will cause the bellows 39 to elongate, thereby raising the lever 37 upwardly and closing the motor switch through the rod 41. When the brine has reached its predetermined temperature, the reverse action takes place, the fall of pressure in the bellows 39 causing the motor switch to open.

Referring to Figs. 2 and 3, the expansion or contraction of the bellows 39, or the expansion of the bellows 38, operates through the rod 41 to tilt a mercury tube 58. This mercury tube comprises a horizontally extending glass tube having upturned terminal ends supporting contact terminals 61 and 62. The terminal 61 is supported in the left-hand end of the tube by a wire 63 extending downwardly therein, and the terminal 62 supported in immediate proximity to the terminal 61 by a wire 64 which is extended down from the other end of the mercury tube and is then bent horizontally to dispose the terminal 62 adjacent the terminal 61. The tube contains a quantity of mercury 65 of just sufficient volume to immerse the lower ends of both terminals 61 and 62 when the left-hand end of the tube is tilted downwardly, but sufficiently small in quantity as to leave these terminals dry and unconnected when the right-hand end of the tube is tilted downwardly only the smallest amount. The tube is hermetically sealed, and also contains an inert gas which reduces any arcing tending to occur at the terminals.

The two terminals or electrodes 61 and 62 connect through external wires 66 and 67

with connecting terminals 68 and 69 of the terminal block 71.

The mercury tube 58 is snapped between the sides or jaws of a spring-clip 72, which is fastened by a screw or bolt 73 to a rotatable hub 74. The screw 73 extends through an upright standard 75 and affords a bearing support therein for the hub 74. An arm 76 extends laterally from the hub 74 and has pivotal connection at 77 with the slotted end of a sleeve coupling 78, into which the lower end of the rod 41 threads. The ends of the rod 41 are threaded for adjustable reception in the coupling members 78 and 79, whereby the effective length of the rod 41 can be lengthened or shortened.

The supporting member 75 is screwed to the insulating connector block 71, and the latter is supported on the vertical wall of the mounting bracket 31 by screws 81 extending through suitable spacing sleeves 82. The housing 42 encloses the mercury tube 58 and connector block 71, this housing having a removable cover for affording ready access to the mercury tube and its connections. The circuit wires 84 and 85 for the electric motor 6 pass through the housing 42, the wire 84 being interrupted for connection with the connector terminals 68 and 69 to include the mercury tube 58 in circuit.

Widespread use of refrigerators embodying the present motor control apparatus over a considerable period of time has demonstrated the reliability and durability of the combination of the bellows and the gas-filled tilting mercury tube. The extreme sensitivity of the bellows to variations in pressure results in a sharp positive operation with only a change of a few degrees in the brine tank 22. The bellows is substantially immune to leakage, and is capable of operating under a high degree of pressure or exhaustion. An exceedingly small movement of the bellows 39 is operative to tilt the mercury tube 58, this mercury tube interposing substantially no inertia to this movement of the bellows. A very slight tipping of the mercury tube 58 is operative to roll the mercury into or out of contact with the terminals 61 and 62. There appears to be no tendency to draw an arc when the mercury breaks contact with the terminals, and consequently there are relatively few service replacements or repairs compared to those necessary with a conventional knife switch.

I claim:

1. In a switch of the class described, the combination of a relatively long second class

lever having fixed pivotal support at one end, a mercury bulb having pivotal mounting in substantially horizontal position in proximity to the free end of said lever and independently of and remote from the pivotal support for said lever, means connecting the free end of the lever with the bulb mounting for tilting the bulb by angular movement of said lever, said bulb having contacts at one end and mercury therein for connecting and disconnecting said contacts by the tilting of the bulb, a temperature responsive bellows co-operable directly with the lever between its pivoted and free ends to swing the lever in a direction to tilt said bulb so that the mercury therein will connect said bulb contacts upon a rise in temperature and a spring independent of the pivotal mounting of the lever and connected with said lever to swing same in a direction to open the mercury connection between said contacts.

2. In a switch of the class described, the combination of a switch housing having an overlying substantially horizontal supporting plate, an upright bracket member mounted upon said plate beyond the ends of the housing, a relatively long second class lever having fixed pivotal support on said bracket member at one end, a mercury bulb having pivotal mounting in substantially horizontal position in the switch housing and in proximity to the free end of said lever, the pivotal mounting for said bulb being independent of and remote from the pivotal support for said lever, an actuating rod pivotally connected to the free end of the lever and extending down through the supporting plate into the switch housing and connected with the bulb mounting within the housing for tilting the bulb by angular movement of the lever, said bulb having contacts at one end and mercury therein for connecting and disconnecting said contacts by the tilting of the bulb, a temperature responsive bellows mounted upon the supporting plate between the upright bracket and the actuating rod and co-operable directly with the lever between its pivoted and free ends to swing the lever in a direction to tilt said bulb so that the mercury therein will connect said bulb contacts upon a rise in temperature and a spring independent of the pivotal mounting of the lever and connected with said lever to swing same in a direction to open the mercury connection between said contacts.

In witness whereof, I hereunto subscribe my name this 15th day of May, 1923.

WILLIAM ERICK BIHL.
